HYDRAULIC PUMP JACK

John H. Suter, Sierra Madre, Calif.

Application March 12, 1938, Serial No. 195,452

3 Claims. (Cl. 121—157)

The object of the invention is to provide a light, portable, and inexpensive power for actuating deep well pumps in oil and water wells.

The apparatus of the invention consists substantially of a power cylinder mounted on and in axial alignment with the well casing; a piston connected with the well pump sucker rods and reciprocating in the cylinder; a source of continuous supply of hydraulic fluid under pressure, and valve mechanism arranged alternately to direct the pressure fluid beneath the piston to produce an upstroke of the pump and to permit the escape of the pressure fluid thus allowing the weight of the rods to produce a downstroke.

This apparatus is capable of various modifications, principally in the valve mechanism, as follows:

In the first and simplest form, the valve by which the direction of pressure fluid flow is periodically reversed is mechanically or hydraulically actuated in one direction and hydraulically actuated in the opposite direction, mechanical means being provided for carrying the valve over a possible dead center;

In the second form a valve actuated as above described is utilized as a pilot valve and the main control valve is hydraulically actuated in both directions;

In the third form the main valve is actuated in the same manner as in the second form but additional provisions are made for keeping the hydraulic supply means (ordinarily a pump and motor) operating under a substantially constant full load.

These various forms are illustrated in the attached drawings, in which

Fig. 1 is a plan diagram of the first form, for locating subsequent figures;

Fig. 2 is an elevation on the valve side of the apparatus, as on the line 2—2 of Fig. 1;

Fig. 3 is a vertical section through the jack assembly 30, as on the line 3—3 of Fig. 1;

Fig. 4 is a vertical section through the main valve of the jack, as on the line 4—4 of Fig. 1;

Fig. 5 is a similar section through the valve assembly of the second form of the invention;

Fig. 6 is an elevation of the valve side of the apparatus of the third form of the invention;

Fig. 7 is a detail of the valve arrangements of the third form;

Fig. 8 is a detail of a modified form of jack piston, and

Fig. 9 illustrates a device for actuating either the main valve or the pilot valve hydraulically at the end of the downstroke.

Referring first to Figs. 1 and 2, 20 is a pump adapted to supply a stream of hydraulic fluid under pressure. This may be a gear or vane pump, for example, and may be driven as by an electric motor 21 directly or through a chain or belt 22. A supply of the hydraulic fluid is maintained in a tank 23, which may be closed as shown and provided with a pressure gauge 24 and a release valve 25, or may be open to the atmosphere.

The numeral 30 generally indicates this form of the well pump actuating assembly, which for brevity will hereinafter be referred to as the jack. This assembly consists essentially of a working cylinder 31, a housing 32, a valve chamber 33, 15 and a spacer 34 which screws or is flanged at its lower end to the upper end of the well casing 35, which thus supports the entire assembly.

Referring now to Fig. 3, the working cylinder 31 is provided with a piston 40 having ring 20 grooves and split rings 41. This piston is hollow as indicated at 42, is formed with one or more openings 43 in its lower face, and has a central boss 44 which is bored to a sliding fit on the polish rod 45. On top of the piston and around the rod is a rod clamp bushing 46 and both the upper face of the piston and the lower face of the bushing are relieved around the rod to receive a packing ring 47. A conventional rod clamp 48 surrounds the rod and rests on the upper end of the bushing. A slip cover 50 of sheet metal surrounding the rod may be used to exclude dust from the upper end of the cylinder.

The lower end of cylinder 31, which may be a casting or a section of steel tubing, is screwed into housing 32 as at 51. Below the end of the cylinder the housing is internally enlarged as at 52 to provide an annular channel around the piston when the latter is at its lowermost position. A thrust pin 53 is brought to a neat sliding fit in a corresponding bore in the housing casting, in such position that its upper end contacts the lower end of the piston as the latter completes its downward travel. The lower end of the pin bears on one end of a rocker arm 54 keyed to a rock shaft 55 which is supported on suitable bearings not shown and, at its forward end, projects through the housing as indicated at 55 in Fig. 2. The opposite end of the rocker arm bears on a cap 56 engaging one end of an open coil spring 57 which is positioned by a rod 58 threaded into the housing at its lower end 59. The tension of this spring is adjusted by a fol-

lower 60, formed to a sliding fit in the upper side of the housing, and an adjusting nut 61.

In a medial position in the housing the polish rod 45 passes through a stuffing box 62 provided with a bolted gland 63. The box is filled with any suitable rod packing, preferably in the two sections 64 and 65 with a lantern ring 66 interposed, this ring draining through a port 67 into the interior of housing 32.

10 The bottom of housing 32 is bolted to or formed integral with a spacer member 68 which is open at its sides to permit access to the stuffing boxes. A flange 69 is bolted to the lower end of this spacer and carries a stuffing box 70 provided with a bolted gland 71 and suitable packing 72. On the lower face of the flange is a projection 73 externally threaded as at 74 to screw into a collar 75 or other fitting carried on the end of pump tubing 76.

20 The spacer member above described has the advantage of exposing the ends of packing members so that leakage may be detected, and of rendering the packing glands accessible for adjustment. In many cases, however, it may be dispensed with and stuffing box 70 utilized for the joint purpose of passing the polish rod out of the cylinder and into the tubing. For example, the lower end of housing member 32 may be flanged and be bolted to a companion flange on the upper end of the tubing string after the packing 72 is placed and adjusted.

25 Referring now to Fig. 4, a valve chamber 33 is formed on or bolted to the face of housing 32 as generally indicated in Fig. 2. This chamber is bored to fit a piston valve 77 and is provided with heads 78 and 79. At one end—the right hand as shown in the figure—a stem 80 is projected from the end of the valve through head 79. The end of this stem engages an adjusting screw 81 carried in a lever 82 which in turn is keyed to the projecting end of rock shaft 55.

30 The piston valve 77 is reduced in diameter for a portion of its length as at 83 and the valve chamber body is provided with a port 84 communicating through a channel 85 with the extreme lower end of working cylinder 31—this channel must not be closed by the piston 40 at any position of the piston. A port 86 formed in the valve chamber body affords communication through pipe 87 with storage tank 23 (see Fig. 2). This port is so positioned that it is wholly closed when valve 77 is in the extreme left hand position and is wholly open when the valve is in the extreme right hand position. A similar port 88 affords communication through pipe 89 with the discharge side of hydraulic fluid supply pump 20. This pump draws fluid from tank 23 through pipe 90 (Fig. 2).

35 In practice, pipes 85 and 89 may communicate with an annular channel surrounding the valve chamber, in which case ports 84 and 88 as shown in the drawings would be merely the portions of this channel continuous to the ends of these pipes rather than individual openings in the valve chamber wall. The length of the reduced portion 83 of the piston is such that these ports, or the channel, are open in all positions of piston valve 77.

40 At the extreme left end of the valve chamber 70 bore a port 91 communicates with a pipe 92 which, as shown in Figs. 2 and 3, is connected into working cylinder 31 at various levels as by branches 93—93, each of which is provided with a stop valve or cock 94—94. The uppermost of 75 these branches enters the cylinder below the po-

sition reached by the lower end of piston 40 at the uppermost end of its stroke and any number of branches may be provided as hereinafter explained.

45 If desired, though the addition is optional, a stem 85 may be projected from the left hand end of valve 77 through head 78, the outer end of this stem being yoked to an arm 96 which is pivoted at its lower end in a bracket 97 projected from the housing. To the upper end of 10 this arm is affixed a curved pipe 98 closed at its ends to afford a runway for a heavy metal ball 99. The bracket 97 is so positioned that travel of the piston valve 77 to its extreme right hand position may move the arm clockwise to the same 15 angle to the right of the vertical, or vice versa without the end of pipe 98 striking the housing.

20 The apparatus above described operates in the following manner. Assuming pump 20 to be in operation and discharging a continuous stream 25 of hydraulic liquid under pressure, and starting with piston 40 at the lower end of its stroke and valve 77 in the position shown by solid lines—pressure fluid passes upwardly through port 88, around the reduced portion 83 of the valve, through port 84 and channel 85 to the lower side of piston 40, lifting it and producing an upstroke 25 of the polish rod and of the sucker rods and the plunger of the submerged well pump.

30 One only of the valves 94 will be open, and when the piston in its upward travel uncovers the opening into the cylinder of the branch controlled by this particular valve, a small quantity of the hydraulic fluid passes through pipe 92 into the left end of the valve chamber, moving valve 77 to the right hand end of its travel. This movement affords communication between ports 84 and 86 and permits the fluid below piston 40 to be ejected through these ports and pipe 87 by the weight of the sucker rod string which is supported by the polish rod and urges the piston 40 downwardly. At the same time ports 88 and 86 are in communication and the fluid discharged by the pump during the period of the downstroke joins that ejected from the cylinder in returning through pipe 87 to tank 23. It will be seen that the length of the stroke is governed by the valve 94 selected for opening.

35 When the piston approaches the end of its downstroke its lower end encounters the upper 50 end of pin 53, which is standing in its uppermost position due to the urgency of spring 57. As the piston sinks to the end of its travel, the pin is depressed, lowering the left end of rocker arm 54 and effecting a partial rotation of rock 55 shaft 55. This rotation, in turn, moves the end of the lever 82 toward the left and reverses the position of valve 77, closing discharge port 86 and admitting pressure fluid through pipes 89 and 85 to the lower end of the cylinder, thus beginning 60 an upstroke.

40 The end of the downstroke is cushioned and destructive impact prevented by the throttling of the ejected hydraulic fluid stream as port 86 is progressively closed by left hand movement of 65 valve 77. As this valve is moved mechanically by the subsiding piston, the point of complete cutoff may be adjusted by changing the position of adjusting screw 80 in lever 82. A further cushioning effect is produced by a layer of compressed air entrapped within hollow piston 40, which is further compressed, as port 86 is progressively closed, by hydraulic liquid flowing into the piston through openings 43.

45 The assembly indicated in Fig. 4 at 95 to 99 in- 75

clusive is for the purpose of positively completing movement of valve 11 in either direction. The initial movement of this valve is produced, as said, by hydraulic fluid admitted at the left end of the valve by the uncovering of one of the ports 93 by upward travel of piston 40. As soon as the valve has moved far enough to partly open port 86, the piston begins to move downwardly and almost immediately covers and seals the port 93 through which the valve is being actuated. If, by this time, the valve has not completed its right hand stroke, the pipe 98 will have been carried far enough to the right to cause ball 97 to roll to the right hand end of tube 98, the weight of the ball then causing the mechanical completion of the valve travel. The same conditions exist at the end of the downstroke.

The hydraulic fluid which actuates the valve in a right hand direction is ejected from the valve chamber when the valve is mechanically moved to the left end of its stroke, but whereas it is taken from below the piston, it is returned through pipe 92 onto the top of the piston, which is at or near the lower end of its travel when the valve reverses. There is thus a small but constant transfer of hydraulic fluid around the piston. To care for this fluid and any additional fluid which may leak past the piston a pipe 100 connects the upper end of working cylinder 31 with the interior of the housing, which is thus utilized as a sump. A pipe 101 similarly drains into the housing any hydraulic fluid which may leak past valve 11. Finally, a pipe 102 connects the bottom of the housing with the suction side of pump 20 (if the oil level and pressure in tank 23 permit) or to the suction of a small independent pump not shown, by which all liquid draining into the housing is returned to the hydraulic fluid system.

In the modification initially referred to as the second form, the general arrangement of the apparatus is identical with that above described with the exception of means used for moving the hydraulic fluid diversion valve. As the location of the cooperating valve mechanisms on the housing of the jack is a matter of convenience only, they are represented diagrammatically in Fig. 5 with connections indicated by which they can be tied into the figures previously described.

Referring to Fig. 5, 33 is the main valve chamber and 103 the pilot valve chamber. The pilot valve chamber is bored to fit the piston valve 104 which is formed with three portions 105, 106, and 107 of reduced diameter. The upper side of the chamber is provided with three ports as shown, ports 108 and 109 communicating with the interior of housing 32 by means of drilled holes 110 and 111. Port 112 communicates through pipe 113 with the source of pressure fluid, as in this instance through pipe 89.

The lower side of the valve chamber is provided with two ports 114 and 115 which communicate respectively with the right hand and left hand ends of main valve chamber 33.

The left hand end of pilot valve chamber 103 communicates with pipe 92 which in turn is connected by branches 93—93 with the working cylinder as shown in Figs. 2 and 3. The right hand end of pilot valve 104 has a projecting stem 80 which engages adjusting screw 81 carried by lever 82 as previously described.

In this form the pilot valve instead of the main valve is actuated in a right hand direction by hydraulic fluid transmitted through pipe 92 from beneath piston 40, and in a left hand direc-

tion by the engagement of piston 40 with pin 53 at the lower end of the stroke, as above described and as shown in Fig. 3.

The main valve chamber is provided with a piston valve 11 and ports similar to those shown in Fig. 4, to-wit: port 84 communicating with the lower end of the working cylinder through pipe 85; port 86 communicating with tank 23 through pipe 87, and port 88 communicating with the source of supply of pressure fluid through pipe 108. As previously described, ports 84 and 88 may be portions of an annulus or common chamber surrounding this portion of the valve bore.

This valve combination functions in a cycle consisting of the following consecutive movements:

1. The jack piston reaches the lower end of its stroke, mechanically moving the pilot valve to the left;
2. Pressure fluid enters right end of main valve chamber, moving main valve to the left;
3. Pressure fluid enters jack cylinder below the piston, producing an upstroke;
4. The jack piston reaches the upper end of its stroke, admitting pressure fluid to the left end of pilot valve chamber and moving pilot valve to the right;
5. Pressure fluid enters left end of main valve chamber, moving main valve to the right;
6. Pressure fluid escapes from beneath piston, permitting it to make a down stroke and to return to position 1, thus completing the cycle.

It will be understood that the directions given in this and the following description are illustrative only and refer to the drawings, the directions of movement obviously being reversible by making appropriate changes in the connecting channels.

To describe the movements in detail: in the positions in which the two valves are shown in Fig. 5, steps 1 and 2 have been completed and pressure fluid from pump 22 is flowing into the cylinder through pipe 89 and channel 85 (port 86 being closed) thus causing the piston to rise.

It being assumed that one of the valves 84 has been opened, the piston continues to rise until the corresponding port in the cylinder wall is uncovered. Pressure fluid from beneath the piston then flows through pipe 92 into the left end of the pilot valve chamber, moving pilot valve 104 to the right. This movement places ports 112 and 115 in communication, and pressure fluid from pipe 113 passes through these ports and pipe 116 into the left end of main valve chamber 33, moving main valve 78 to the right. In the course of this movement the fluid residing in the right end of the valve chamber is ejected through pipe 117 and passes through pilot valve ports 114, 108, and 110 into housing 32, from which it is withdrawn as above described.

The right hand movement of the main valve uncovers port 86 and the fluid beneath the piston escapes (under the urgency of the weight of the rod string) through channel 85 and ports 84 and 86 into pipe 87, through which it returns to the suction side of the pressure pump. At the same time ports 88 and 86 are in communication through annulus 83 and the delivery of the pressure pump is thus bypassed back to the suction side through pipe 87.

When the piston reaches the lower end of its stroke, it encounters pin 53 (Fig. 3) and through arms 54 and 82 moves pilot valve 104 to the left. Pressure fluid from pipe 113 then passes through ports 112 and 114 and pipe 117 into the right end 73

of main valve chamber, moving the main valve to the left and ejecting the fluid from the left end of the main valve chamber through pipe 118 and pilot valve ports 115, 109, and 111 into housing 32. With the main valve in the left hand position, port 86 is closed and pressure fluid from pipe 89 passes through ports 88 and 84 and channel 85 into the cylinder beneath the piston, thus initiating a second upstroke and completing the cycle of movements.

In the use of either of the above forms, a portion of the dead weight of the rod string may be counterbalanced by carrying a suitable pneumatic pressure on the hydraulic fluid column in tank 23. Thus, for example, if it is found that a hydraulic fluid pressure of 300 pounds per square inch is required to raise the piston and its load at the maximum speed required and that the weight of the load is sufficient to return the piston against a back pressure of 250 pounds, the latter pressure may be maintained on the air above the oil column in tank 23 by constantly supplying a minute quantity of air to the tank and setting relief valve 25 at the pneumatic pressure required. This air may well be supplied by an auxiliary pump used to return drainings from housing 32 to the pressure side of the system by so adjusting its capacity as to cause it to take in a little air along with the drainage liquid.

The forms above described use the hydraulic fluid under a fluctuating pressure which rises to a peak depending on the load during the pumping stroke and drops to the back pressure (if any) in tank 23, plus frictional resistance of return pipes and ports, during the return stroke. Thus the pump does useful work only during the pumping stroke (the upstroke of the jack piston) while during the return stroke the hydraulic fluid is bypassed without doing any work. Thus during more or less half the period of the stroke cycle the hydraulic pressure pump is idling against the considerable back pressure required to prevent unduly rapid drop of the rod string.

In the third form of the invention this waste of power is avoided and a smaller pump and motor made available by directing a substantially constant hydraulic stream of reduced volume into a storage vessel maintained under a slightly fluctuating pneumatic pressure sufficient at its lowest point to raise the jack piston with its load, and admitting fluid to the jack cylinder from this vessel instead of directly from the pump.

This arrangement, which functions in the general manner above described but with the use of two storage tanks and a somewhat different valve arrangement, avoids any bypassing of hydraulic fluid while permitting the pump to run constantly.

Referring to Figs. 6 and 7, the third form has a pump 20 driven by a motor 21, a high pressure fluid supply tank 120 and a low pressure fluid supply tank 23. The pump discharges only into tank 120, through pipe 89, and takes suction only on tank 23, through pipe 90.

The main valve chamber 121 is provided with a piston valve 122 having two reduced portions 123 and 124. The pilot valve chamber 125 is provided with a piston valve 126 having three reduced portions 127, 128, and 129. The right hand end of piston 126 projects as at 130 and is engaged by the end of lever 82 to be mechanically moved toward the left as above described in connection with the first form of the apparatus. The left hand end of the pilot valve chamber

communicates through pipe 92 with any one of a series of ports formed in the side of working cylinder 31, also as previously described.

With the pilot valve in the position shown and the piston at the end of the down stroke, pressure fluid from high pressure tank 120 passes through pipe 130, ports 131 and 132, and pipe 133 into the left end of main valve chamber 121, thus moving main valve 122 to the right hand end of its stroke. This movement places ports 134 and 135 in communication, simultaneously closing port 136, and high pressure fluid flows from tank 120 through pipes 137 and 138 into the lower end of working cylinder 31, raising the piston. The fluid displaced from the right end of the main valve chamber by this right hand movement passes through pipe 139, ports 140 and 141, and pipe 142 into low pressure tank 23 or into housing 32.

When the piston 40 has been lifted to such height as to uncover one of the ports 94, pressure fluid flows through pipe 92 into the left end of pilot valve chamber 125, moving pilot valve 126 to the right hand end of its stroke. This movement places ports 131 and 140 in communication and pressure fluid from tank 120 flows through pipe 130, ports 131 and 140, and pipe 139 into the right end of main valve chamber 121, moving main valve 122 to the left end of its travel. In this position communication between ports 135 and 134 is interrupted and pressure fluid passes from the lower end of the working cylinder 31 through pipe 138, ports 135 and 136, and pipe 143 into low pressure tank 23. The fluid displaced in this left hand movement of the main valve passes through pipe 133, ports 132 and 144, and pipe 145 into tank 23 or into housing 32.

A suitable means for maintaining a pneumatic cushion above the oil level in tank 120 is shown in Fig. 6. This arrangement consists of any suitable small pump 170 taking suction from the bottom of housing 32 as through pipe 102. This pump discharges into the upper part of tank 120 through pipe 171, thus returning to the circulating supply of hydraulic fluid the liquid collecting in the housing as previously described. The speed of this pump should be so adjusted that in addition to removing liquid from the bottom of the housing as fast as it collects, a small continuous supply of air will also be drawn into the suction of the pump and discharged into tank 123. This air passes out of tank 120 through pipe 172 in which is interposed a relief valve or pressure regulator 173 set at the working pressure which it is necessary to maintain in this tank. From this regulator the air passes through pipe 174 to a second regulator 175 adjusted to relieve at a pressure lower than that fixed by regulator 173. A pipe 176 is branched from pipe 174 into the top of tank 23 and thus the pressure in this tank is governed by the adjustment of regulator 175. The air lifted by pump 170 is thus finally discharged from the system through pipe 177. Regulator 175 may be adjusted to maintain a superatmospheric pressure in tank 23 to partially counterbalance the load on the jack or, if preferred, it may be backed off in order to maintain tank 23 at atmospheric pressure.

A modified form of piston arrangement which has advantages over that shown in Fig. 3 is illustrated in Fig. 8. In this form the piston 40 is provided with a riser 150 surrounding the polish rod and split at its upper end 151 to be clamped to the polish rod in the usual manner. This riser is flanged at its lower end and bolted to the piston 75

head as at 152. A cap ring 153 is screwed or otherwise attached to the upper end of jack cylinder 31 and is projected inwardly to form a shoulder 154 to engage the upper end of the piston while allowing clamp 151 to pass through. The overflow opening 155 into pipe 100 is so located that clamp 151 will project above ring 153 when this opening is partly uncovered by upward movement of the piston. To insure against upward slippage of the piston on the polish rod it is often desirable to place an independent rod clamp 156 above clamp 151.

One advantage of this arrangement is that the piston may be raised by hydraulic fluid pressure until the opening of port 155 stops its further movement, after which the polish rod may be raised or lowered as regards the piston by loosening clamps 151 and 156. Another advantage is that by disconnecting the polish rod below the jack assembly and the assembly from the tubing head and the pipes through which hydraulic fluid is conveyed, the entire jack assembly may be swung up in the derrick from the upper end of the polish rod by raising the rod until the upper end of piston 40 engages shoulder 154.

For the left hand movement of either the main valve of the first form or the pilot valve of the second or third, it is possible to substitute for the mechanical linkage indicated by numerals 53 to 60 and 81-82 of Figs. 3, 4, 5, and 7 a means for actuating the valve hydraulically in response to the downward movement of the piston at the end of the stroke.

In Fig. 9, 31 is a fragment of the lower end of the jack cylinder, 32 the housing member, and 40 the piston shown in preceding figures. A tappet valve 160 is passed into the lower end of the cylinder through the upper wall of the housing and is supported in position by a spring 161 of such stiffness as to prevent the valve from being forced downwardly by the maximum fluid pressure existing in the cylinder. The body of the housing surrounding the tappet valve is provided with three channels, 162 leading from the interior of the cylinder to the bore 163 in which the tappet valve slides, 164 leading from the bore to the interior of housing 32, 165 leading to the right hand end of main valve chamber 33 (Fig. 4) or pilot valve chamber 103 (Fig. 5) or 125 (Fig. 7) as the case may be.

The tappet valve has two grooves 166 and 167 so arranged that when piston 40, in its downward movement, has depressed the tappet valve to the end of its travel, channel 164 is closed and channel 162 is placed in communication with channel 165 through groove 166, thus permitting hydraulic fluid to pass into the right end

of the main or pilot valve chamber and move the valve to the left hand. As the piston then rises and the spring returns the tappet valve to the position shown in Fig. 9, channel 162 is closed and channel 165 is placed in communication with channel 164 through groove 167, thus permitting the fluid ejected from the main or pilot valve chamber by right hand movement of the valve to pass into housing 32 from which it is removed as previously described.

I claim as my invention:

1. In a hydraulic pump jack having a cylinder and a piston vertically reciprocating therein: a main valve arranged alternately to admit hydraulic fluid to and release said fluid from the lower end of said cylinder; a pilot valve arranged to reciprocate said main valve by admitting hydraulic fluid alternately to its opposite ends; mechanical means actuated by contact with said piston for moving said pilot valve to one end of its travel at the end of the downstroke, and hydraulic means actuated by pressure transmitted from within said cylinder for moving said pilot valve to the opposite end of its travel at the end of the upstroke.

2. In a hydraulic pump jack having a cylinder and a piston vertically reciprocating therein: a main valve arranged alternately to admit hydraulic fluid to and release said fluid from the lower end of said cylinder; a secondary valve actuated by contact with said piston to transmit fluid from the lower end of said cylinder to said main valve and thereby to move said main valve hydraulically to the fluid admitting position at the end of the downstroke, and means for transmitting hydraulic fluid from the upper part of said cylinder to said main valve and thereby to actuate said main valve to the fluid releasing position at the end of the upstroke.

3. In a hydraulic pump jack having a cylinder and a piston vertically reciprocating therein: a main valve arranged alternately to admit hydraulic fluid to and release said fluid from the lower end of said cylinder; a pilot valve arranged to reciprocate said main valve by admitting hydraulic fluid alternately to its opposite ends; a secondary valve actuated by contact with said piston and controlling a channel for transmitting hydraulic fluid from said cylinder to said pilot valve and thereby moving said pilot valve hydraulically to one end of its travel at the end of the downstroke, and means for transmitting hydraulic pressure to said pilot valve from the upper part of said cylinder for moving said pilot valve to the opposite end of its travel at the end of the upstroke.

JOHN H. SUTER.
